UNITED STATES PATENT OFFICE.

ALBERT J. HARNACK, OF PITTSBURGH, PENNSYLVANIA.

FLASH-LIGHT.

1,148,839.

Specification of Letters Patent.

Patented Aug. 3, 1915.

Application filed August 29, 1914. Serial No. 859,233.

To all whom it may concern:

Be it known that I, ALBERT J. HARNACK, a citizen of the United States, residing at Pittsburgh, in the county of Allegheny and State of Pennsylvania, have invented certain new and useful Improvements in Flash-Lights, of which the following is a specification.

The present invention relates to improvements in flashlights, and more particularly to portable flash lights.

The primary object of the invention is the provision of a flash light in which the conductors engaged by the operating switch 15 may be concealed by embedding the same in the material of the casing upon which the switch is mounted, and in which the battery and the globe are located, or which may be concealed by a removable tape or the like, or which may be entirely or partly exposed.

Another object of the invention is the provision of a flashlight, wherein the switch for controlling the same can be locked so as 25 to maintain the circuit open and to prevent accidental closing of the circuit, which would tend to weaken the battery and decrease the volume of light and the efficiency of the device.

Still another object of the invention is the provision of a device such as above described, having a conductor formed in two sections disposed with their adjacent ends in spaced relation and a switch secured to 35 the casing and adapted upon sliding movement to engage the ends of said conductor sections, thereby closing the circuit and flashing the light.

Another object of the invention is the 40 provision of a flashlight, in which short circuiting is prevented and in which insulating means such as a ring made from fiber, or a non-conducting fluid is introduced to prevent the flashing of the light in the event 45 that the device is placed on any object which might act as a conductor, by engaging the opposite end caps, or one of the end caps and the switch.

A further object of the invention is the 50 provision of a flashlight, such as above described, in which the various parts thereof will be comparatively simple and inexpensive to manufacture, reliable and efficient in use, and readily operated.

In effecting the above desiderata, the 55 present invention resides in the novel fea-

tures of construction, formations, combinations and arrangements of parts to be hereinafter more fully described, claimed and illustrated in the accompanying drawing, 60 forming a part of this application, and in which:

Figure 1 is a longitudinal sectional view, taken through a flashlight constructed in accordance with the present invention, 65 showing the thicknesses of material slightly exaggerated in order to more clearly bring out the invention; Fig. 2 is a transverse sectional view taken on the line 2—2 of Fig. 1, with the battery removed; Fig. 3 is a detail 70 transverse sectional view taken on an enlarged scale, on the line 3—3 of Fig. 1; Fig. 4 is a longitudinal sectional view taken on the line 4—4 of Fig. 3, on substantially the same scale; Fig. 5 is a view showing the 75 several parts of the switch separated; and Figs. 6, 7, 8 and 9 are enlarged detail transverse sectional views showing modifications in the form of conductors, and Fig. 10 is a view illustrating the use of non-conducting 80 fluid.

Referring to the accompanying drawing by similar characters of reference throughout the several views, the numeral 6 denotes in general a flashlight constructed in accordance with my invention, comprising a tubular casing 7, formed from any desired non-conducting material, preferably of a fibrous nature, the same being reinforced at its opposite ends by metal sleeves 8 and 9, 90 which are held upon the said tubular casing 7, by rivets 10 or the like. The rear end of the casing 7 is closed by a cap 11, threaded upon the sleeve 8 as clearly shown in Fig. 1. A spring 12 of preferably a helical formation, gradually decreasing in diameter from its inner end to its outer convolution, 95 is disposed within the cap 11, and bears against the rear end of a storage battery 13, by which the light is operated. The forward end of this battery is provided with a contact post 14 designed to engage the socket 15 of an incandescent lamp bulb 16, shown in conventional form in Fig. 1.

The socket 15 is threaded in the minor 100 end of the bell-shaped reflector 17, the major end of which is flanged to engage the inwardly directed end of the sleeve 9, being held in position by a cap 18, threaded as shown in Fig. 1, on the before described 11 sleeve 9, and formed with a flange 19, which by its insertion between the adjacent por-

tions of the sleeve 9 and cap 18, locks the reflector against displacement. This cap also locks the lens 20 in position between the flanged end of the reflector and the inwardly directed flange of the said cap. It will be thus seen that the current from the battery 13, passes to the socket 15 and thence to the reflector 17, while if desired, in order to prevent the current from passing to the sleeve 9 and cap threaded thereon, the flanged end of the reflector 17 may be insulated. One manner of insulating this reflector, may reside in interposing a non-conducting ring between the flanged end of the reflector and the end of the cap 18, or by coating the flanged end of the reflector with any non-conducting substance, such as a quick solidifying liquid, or the like, or by use of non-conducting fluid as shown in Fig. 10, but I do not desire to be limited to such means as above mentioned, but may employ any other method which will answer the purpose.

Disposed within the casing 7 and secured to the inner side thereof are two flat conductor sections 21 and 22, the former of which engages the sleeve 8, while the opposite end of the conductor section 22 is offset to yieldingly engage the side of the reflector as shown at 22^a, in Fig. 1. These sections 21 and 22 of the conductor are retained in position by rivets or the like, one of which passes through the conductor 22, adjacent the offset end 22^a, and in order to prevent the current from passing through this conductor to the sleeve 9 and thence to the cap 18, a thin strip of fiber filament or other insulating material is interposed between the sleeve 9 and this adjacent rivet.

The operating switch is shown at 23, and consists of a housing 24, secured to the casing 7, by the end rivet 25, and the side rivets 26. The rivet 25 passes through the conductor section 21, connecting the same with the said housing 24. A push button 27 is slidable upon the outer side of the housing 24. This button is preferably rounded as shown, and formed with fingers 28, which depend from opposite sides thereof, and extend through slots 29, in the top of the housing, in spaced relation, thus providing a means for slidably connecting the said button thereto. These fingers 28 are bent at 30 to engage a spring contact member 31, formed with notches 32 in the opposite edges thereof, to receive the said fingers 28 as clearly shown in Fig. 3, consequently firmly securing the spring contact member to said button so that, upon longitudinal movement of the button 27, the contact member 31 will be moved longitudinally within the housing, being at all times concealed therein.

A hook 33 is formed at one end of the contact member 31 and is formed for en-

gagement with the boss 34, formed by depressing a part of the housing at the rear end thereof, for the purpose of holding the contact member in an inoperative position as shown in Fig. 4, and preventing accidental closing of the switch, through jarring or the like. The forward end of the spring contact member 31 is curved inwardly as at 35, for sliding engagement with the exterior of the casing 7, and engagement with the rivet 36, which passes through the end of the conductor 22, and extends within the housing 24. Obviously upon the forward movement of the push button 27, the curved end 35 of the member 31, will slide forwardly along the outer side of the casing 7, and over and upon the rivet 36, in which position it will be held by frictional engagement, retaining the circuit closed, as shown in Fig. 4.

As shown in Fig. 6, the conductor sections 21 and 22, need not be secured to the inner side of the casing 7, but it is sometimes preferred to conceal the same by embedding the same in the wall of the casing as shown in the above figure.

In Fig. 7 the conductor is shown triangular in cross section, embedded in the wall of the casing 7, but not concealed, while in Fig. 8 this same form of conductor is shown concealed by a removable tape or the like.

In Fig. 9, it will be seen that the conductor can be partly concealed if for any purpose it is desired to do so.

It should be understood in this connection, that I am not to be limited to the specific details of construction herein described and illustrated in the accompanying drawing, but may resort to various minor changes within the scope of the appended claim without departing from or sacrificing any of the advantages of the invention.

From the foregoing it will be manifest that a flashlight is provided which will fulfil all the necessary requirements of such a device.

Having thus fully described this invention, what I claim as new and desire to protect by Letters Patent is:

In a flash light such as described, a casing, illuminating means in said casing including an electric circuit, contact members incorporated in the circuit and embedded in the casing with the ends thereof in spaced relation and exposed to the outer side of said casing, a housing secured to the casing and concealing spaced ends of the contact members, said housing having spaced longitudinally extending slots formed in the outer side thereof, a push button slidable upon said housing, fingers formed upon the push button and passing through the slots in the housing, a spring contact member slidable within the housing and having notches in the opposite sides thereof in

which the fingers of the push button are engaged, whereby upon movement of the push button the spring contact member will be moved longitudinally of the housing, said 5 housing being in contact with one of the spaced contact members, a rivet passing through the other of the contact members and securing the same to the housing for engagement with the circuit in closed position, and a depression provided in the hous-
10

ing for engaging the other end of the spring contact member whereby the latter will be locked with the circuit in open position.

In testimony whereof I affix my signature in presence of two witnesses.

ALBERT J. HARNACK.
